UNITED STATES PATENT OFFICE.

FELIX GOTTLICHER, OF BURLINGAME, CALIFORNIA.

DESIGN FOR A SOAP TRAY.

Application filed June 10, 1925. Serial No. 13,727. Term of patent 3½ years.

To all whom it may concern:

Be it known that I, FELIX GOTTLICHER, a citizen of the United States, and resident of Burlingame, county of San Mateo, State of California, have invented a new, original and ornamental Design for a Soap Tray, of which the following is a specification, reference being had to the accompanying drawing, forming part thereof.

Fig. 1 is a perspective view of the device.

Fig. 2 is a transverse view on line 2—2 of Fig. 3.

Fig. 3 is a front elevational view.

I claim:

The ornamental design for a soap tray, substantially as shown.

FELIX GOTTLICHER.
